UNITED STATES PATENT OFFICE.

BEN K. FORD, OF OAK PARK, ILLINOIS, ASSIGNOR TO AMERICAN CAN COMPANY, OF NEW YORK, N. Y., A CORPORATION OF NEW JERSEY.

PROCESS OF MAKING JACKETED CANS.

1,272,789.

Specification of Letters Patent. Patented July 16, 1918.

Application filed November 22, 1913. Serial No. 802,373.

To all whom it may concern:

Be it known that I, BEN K. FORD, a citizen of the United States, residing in Oak Park, in the county of Cook and State of Illinois, have invented a new and useful Improvement in Processes of Making Jacketed Cans, of which the following is a specification.

This invention relates to improvements in process of making jacketed cans.

10 Objects of the invention are to provide a simplified process of making a jacketed can having the main portion of the jacket formed by a tube composed of layers of paper; to provide a process of making a jacketed can in such a way that the can is provided with a jacket covering substantially all walls thereof; and to provide a process wherein the manner of forming the joint between the top and the body of the can insures a strong, rigid and uniform construction.

The invention furthermore consists in the improvements in the steps and novel combinations of the steps of the process as herein shown, described or claimed.

In the drawing forming a part of this specification I have illustrated various steps used in carrying out my improved process, and in said drawing Figure 1 is a vertical 30 diametrical sectional view of the paper jacket, the same being shown with an annular can-supporting strip secured to the bottom thereof and the dotted lines indicating the wooden disk bottom of the jacket. Fig. 2 is a sectional view of the can body and top, the same being separated and showing in detail the manner of forming the top before it is soldered to the can body proper. Fig. 3 is a sectional view of the can and 35 jacket as the same are assembled and showing the can top as already soldered to the can body, and Fig. 4 is a detail sectional broken view showing the finished article produced by my process.

40 In carrying out my process, a cylindrical paper tube 10 is formed by winding several layers of paper on top of each other by any well-known method, the tube being cut to proper length to fit the can and, as will be understood, this tube is made of such a size 50 that it will slip over the can to be covered thereby. After the paper tube 10 is formed, it has secured thereto an annular binding and supporting metal strip 11, the lower 55 edge of which is curled outwardly and up-

wardly over the lower edge of the tube, the inner edge of said annular strip forming a support or shelf 12 as shown. A bottom disk 13 of wood or other material is then placed within the tube on the supporting ledge 12 and the jacket is now ready to receive the can.

As shown in Fig. 2, the can body 14 has secured thereto a bottom 15 by a double seam or in any other suitable manner. The can top is of peculiar construction and is provided with a countersunk portion 16 surrounded by an upright annular wall 17 adapted to fit within the open top of the can body 14, said top being provided also with an outwardly extended peripheral flange 18 located in a plane intermediate the top and bottom of the annular wall 17 for a purpose hereinafter specified. The can top formed in the manner above described, is placed within the can body and soldered thereto as indicated at 19 in Fig. 3. The can body and top in this condition are next placed within the jacket as shown in Fig. 3, after which a top disk 20 of wood or other suitable material is placed in the countersunk portion of the can top. Following this, the peripheral flange 18 of the can top is curled downwardly over the upper edge of the paper tube jacket and the latter is pressed inwardly against the wall of the metal can as indicated at 21 in Fig. 4. The upper portion of the wall 17 of the can top which, as clearly shown, is of double thickness, is folded inwardly and pressed down onto the top 20 to secure the latter in place, as shown most clearly in Fig. 4.

From the preceding description it will be seen that I have provided a simple and relatively inexpensive process for manufacturing jacketed cans in which the jacket extends over all walls of the can and that the manner of securing the tube and top of the can by means of the can top itself, insures a strong and rigid construction.

100 By the use of the term "paper" I wish it to be understood that I mean any fibrous material which can be formed into a jacket in the manner described and that although I have herein described the process as applied to the manufacture of a cylindrical can and jacket, yet it will be understood that the process can be carried out with jacketed cans of different shape and construction. It will furthermore be understood that it is imma- 105 110

terial whether the jacket is formed before the can or vice versa or whether both are formed simultaneously before the two parts are assembled. In the drawings the thicknesses of the layers of paper and metal are exaggerated in order to more clearly illustrate the construction.

I do not claim herein the can or container, the same being the subject of my pending 10 application Serial No. 802,372, filed Nov. 22, 1913.

I claim:

1. A process of manufacturing jacketed cans, which consists in first separately forming a complete circumferentially continuous jacket body, a complete can body, and an incomplete flanged cover adapted to fit within the can body and having an edge adapted to extend beyond the edge of the can and 15 jacket bodies; and second, assembling the same by inserting the can body longitudinally within the jacket and the cover within

the body; and, third, bending the edge of the cover to clench the jacket and can bodies to each other and to the cover. 25

2. The process of manufacturing jacketed cans, which consists in first providing independent jacket and can bodies, a closure having an outstanding flange and an upstanding flange located at its edge, and a jacket 30 disk; and second, assembling said parts, the can body within the jacket body, the closure within the can body and the disk with the closure; and third, bending said flanges in opposite directions, the outstanding flange 35 to clench the jacket and can bodies together and to the closure and the upstanding flange to incase the end jacket disk.

Signed this 18th day of November, 1913, in the presence of two witnesses.

BEN K. FORD.
